UNITED STATES PATENT OFFICE.

MICHAEL QUIN, OF GALVESTON, TEXAS.

IMPROVEMENT IN BALE-TIES.

Specification forming part of Letters Patent No. **135,938**, dated February 18, 1873.

To all whom it may concern:

Be it known that I, MICHAEL QUIN, of Galveston, in the county of Galveston and State of Texas, have invented a new and improved mode of fastening iron or other metal ties or bands on cotton-bales and other packages usually put up in iron bands; and I do hereby declare the following to be a full and exact description of the construction and use of same, reference being had to accompanying drawing making a part of this specification.

The nature of my invention consists in providing a buckle or clasp, of which A is a perspective view, and B a side view, and C an end view, to be formed out of iron or any other metal or substance of sufficient strength, and cut, as presented in diagram E, with the slots H cut out, then the sides F to be turned up, as in perspective view A, which clasp or buckle is to be used with an iron or any other metal band, with alternate notches or projecting shoulders cut in the same, as shown in D;

and the said bands may be provided with one or more of the notches, offsets, or shoulders, as shown in the drawing, at the will of the manufacturer, or as expediency may require; and the manner of applying said fastening shall be by placing the notched band D¹ between the sides F in the clasp, and drawing the band down until the shoulder D² shall have entered the slot H provided for it; then the other end of the band shall be brought around and inserted in a corresponding manner, when the fastening is complete.

What I claim as my invention, and desire to secure by Letters Patent, is—

The buckle, as constructed, in combination with the notched band, substantially as described.

MICHAEL QUIN.
